UNITED STATES PATENT OFFICE.

PERCY TRIPP BAILEY, OF MIDDLETOWN, RHODE ISLAND.

FENCEPOST ATTACHMENT.

Original application filed October 8, 1919, Serial No. 329,316. Divided and this application filed October 4, 1921. Serial No. 505,365.

To all whom it may concern:

Be it known that I, PERCY T. BAILEY, a citizen of the United States, and a resident of Middletown, in the county of Newport 5 and State of Rhode Island, have invented a new and Improved Fencepost Attachment, of which the following is a full, clear, and exact description.

This invention relates to fences and is a 10 divisional application of my application Serial No. 329,316. The object of the invention is to provide an improved construction of attachment at the top for retaining a pipe or bar in position.

15 Another object of the invention is to provide an attachment for the top of fence posts which will give additional fence structure and at the same time present an ornamental appearance.

20 A still further object in view is to provide an improved construction of pipe holding means at the top of posts, which in addition, presents means for carrying fencing wire and thereby permit the use of a comparatively 25 short post and at the same time provide a maximum height of fence.

In the accompanying drawings—

Figure 1 is a side view of a post and attachment disclosing one embodiment of the 30 invention, certain parts being shown in section.

Figure 2 is a front view of the structure shown in Figure 1, the lower part being broken away.

35 Figure 3 is a disassembled view of a pair of clamping arms embodying certain features of the invention.

Figure 4 is a sectional view through Figure 1 approximately on line 4—4.

40 Referring to the accompanying drawings by numeral, 1 indicates a post similar to that disclosed in my Patent No. 1,190,080, said post being designed to carry fencing wire 2 held in place in any desired manner, as for 45 instance, by tying members 3. In some instances it is desired to increase the height of a fence considerably or slightly and in addition to provide an ornamental top or finish to the fence. When it is desired to increase 50 the effective height of the fence, some additional fencing material is connected to the post so as to extend above the same.

In the present instance, the effective height has been increased by the provision 55 of clamping arms 4 and 5, arm 5 being pro-

vided with a pressed out hook member 6 which carries a top wire 2'. This wire may be arranged in line with the top of the post as shown in Figure 1 or may be made slightly higher if desired by pressing out the 60 hook member 6 at a higher point. The clamping arms 4 and 5 are each provided with a cut 7 which extends approximately half across the width of the arms so that they may be interlocked as shown in Figures 1 and 65 2. These arms are provided with rounded pipe gripping portions 8 and 9 and with substantially rounded fence gripping sections 10 and 11. The portions 8 and 9 extend upwardly and form the ornamental extending 70 lugs 12 and 13. The portions 8 and 9 are adapted to grip tightly a rod or pipe 14 which acts as a sort of ridge pole or top bar to the fence. A bolt 15 extends through suitable slots 16 and 17 in the clamping arms 75 4 and 5 and acts to firmly clamp said arms to the post. Ordinarily the arms are positioned on the post so that the pipe 14 will rest on top of the post. However, under some circumstances, the post may be set in the 80 ground to a greater depth than others or to a less depth or possibly it may be set in a hollow of the land. The arms 4 and 5 may be raised and lowered to take care of slight inner qualities or difference in effective 85 heights of the post by reason of the slots 16 and 17. Preferably, a round opening is provided in the post 1, though if desired, slots could be provided without departing from the spirit of the invention. 90

What I claim is:—

1. A fence post attachment comprising a pair of arms, adapted to grip a horizontally extended pipe, means for connecting the arms to a fence post, said arms being adjustable in respect to said means for varying the distance between said pipe and said post, said arms being provided with slots for locking one arm into the other. 95

2. An attachment for fence posts comprising a pair of arms adapted to grasp the top member of the fence, said arms being formed adjacent their top ends with transverse slots for permitting one arm to interlock in the other, said arms having substantially arc shaped sections at the opposite end, and a clamping bolt extending through said arc-shaped sections, and the fence post for clamping the arms to the posts. 105

3. An attachment for fence posts com- 110

prising a pair of attachable arms adapted to be secured to the top end of the post, said arms interlocking with each other upon said top end of the post and leaving therebetween 5 a space for fencing material to pass therethrough, each arm having an arc-shaped section adjacent one end and a longitudinal slot approximately in the center of each section, and a clamping bolt extending through said 10 said slots and through the post for clamping the arms of the post, said slots permitting a vertical adjustment of the arms with respect to said bolt.

4. A fence post attachment comprising an 15 arm arcuated adjacent one end to fit on the

side of the post, and arcuated at the opposite end in a plane transverse to the first mention arcuation for receiving a fence pipe, said attachment adjacent the last mentioned end presenting a transverse slot adapted to receive the end portion of a similar attachment.

5. A fence post attachment comprising an arm having an arcuated section adjacent its lower end and presenting a longitudinal slot, and a transversely arcuated section at the upper end presenting a slot transverse to the first mentioned slot. 20 25

PERCY TRIPP BAILEY.
